UNITED STATES PATENT OFFICE.

HENRY G. SAAL, OF CHICAGO, ILLINOIS.

DISPLAY-STAND.

1,263,807.

Specification of Letters Patent. Patented Apr. 23, 1918.

Application filed June 21, 1917. Serial No. 176,006.

To all whom it may concern:

Be it known that I, HENRY G. SAAL, citizen of the United States, residing at Chicago, in the county of Cook and State of Illinois, have invented a certain new and useful Improvement in Display-Stands, of which the following is a full, clear, concise, and exact description.

My invention relates to display stands and has a number of objects and advantages in view. The stand of my invention includes a pedestal, an upright carried thereby and projecting upwardly therefrom, object supporting fingers carried by an upper portion 10 of the upright and a platform or platforms for supporting other objects and so related to the fingers that the various objects carried by the display stand will not interfere with each other.

These characteristics of my invention are realized by the preferred embodiment of the invention shown by the accompanying drawings in which Figure 1 is a view in front elevation, the suspended objects at the front 20 of the stand being removed for the sake of clearness; Fig. 2 is a plan view of the top part of the stand; Fig. 3 is a view on line 3—3 of Fig. 1 excepting that the object at the front of the stand is present in this view; Fig. 4 is a view on line 4—4 of Fig. 1 with the object at the front of the stand added; Fig. 5 is a view from beneath of the structure as it appears in Fig. 6; Fig. 6 is a sectional view on line 6—6 of Fig. 5; Fig. 7 is 30 a view in elevation of the top part of the structure with suspended objects thereon; Fig. 8 is a view on line 8—8 of Fig. 6; Fig. 9 is a perspective view of the lower platform; Fig. 10 is a view on line 10—10 of Fig. 3; Fig. 11 is a view on line 11—11 of Fig. 9; and Fig. 12 is a view illustrating the component parts of the structure.

Like parts are indicated by similar characters of reference throughout the different 45 figures.

The display stand includes a pedestal 1 and an upright 2 carried by and projecting upwardly from the pedestal. An object supporting plate 3 is carried at the upper 50 end of the upright, this plate being formed with transversely curved upward bulges that are disposed along lines extending across the

plate to form plate strengthening ribs 4, these bulges in the plate being integrally continued beyond the plate and there being 55 upwardly directed from the plate to form fingers 5 that are in the form of hooks and upon which fingers objects 5¹ that are to be displayed may be hung. A platform 6 is carried by the upright at a lower portion 60 thereof and has depressions 7 therein forming underlying seats for the objects 7¹ that are to rest upon this platform, said platform having notches 8 in its edge portion that are located between adjacent seats 7 in 65 the platform 6, these notches 8 being provided for receiving objects 5¹ hung upon said fingers to position them between the objects 7¹ upon the platform 6. An additional platform 9 is provided above the platform 6 and of a size smaller than the platform 6 to clear the objects 5¹ hung upon 70 said fingers. A positioner 10 is located above the additional platform 9 and is smaller than the platform 6 also to clear the objects 75 5¹ hung upon the fingers 4. The positioner 10 is desirably in the form of a plate provided with openings 10¹ overlying the additional platform and located beside the vertical planes containing the upright 2 and 80 fingers 5 whereby the objects 9¹ supported upon the additional platform 9 are clear of the objects 5¹ hung upon the fingers. The notches 8 in the platform 6 are desirably 85 farther away from the upright than the object engaging portions of the fingers whereby the objects 5¹ hung from the fingers are inclined upwardly toward the upright. The objects 5¹ happen to be mop handles 90 carrying mops at their lower ends and provided with screw eyes 5² at their upper ends that are passed over the fingers or hooks 5. The objects 7¹, 9¹ happen to be in the form of tubes or cans that contain oil or other 95 liquid with which the absorbent strands of the mops are to be treated. Each of the object supporting plates 3, 6 and 9 is assembled with the upright 2 by means of a collar 11 having a finger formation 12 integrally 100 formed with the collar and projecting transversely therefrom, said finger formation being fastened to the adjacent object supporting plates to assemble the collar and such plates.

While I have herein shown and particularly described the preferred embodiment of my invention I do not wish to be limited to the precise details of construction shown as 5 changes may readily be made without departing from the spirit of my invention, but having thus described my invention I claim as new and desire to secure by Letters Patent the following:

- 10 1. A display stand including a pedestal; an upright carried by and projecting upwardly from the pedestal; a plurality of fingers carried at the upper portion of the upright and upon which objects to be displayed 15 may be hung; a platform carried by the upright at a lower portion thereof and having depressions therein forming seats for the objects that are to rest upon this platform, said platform having notches in its 20 edge portion that are located between adjacent seats in said platform and provided for receiving objects hung upon said fingers to position them between the objects upon said platform, the notched portions of the 25 platform being farther away from the upright than the object engaging portions of the fingers whereby the objects hung from the fingers are inclined upwardly toward the upright; an additional platform above the 30 first platform and of smaller size to clear the objects hung upon said fingers; and a positioner located above the additional platform and smaller than the first platform also to clear objects hung upon said fingers 35 and provided with openings located beside the vertical planes containing said upright and fingers whereby the objects supported upon the additional platform are clear of the objects hung upon the fingers.
- 40 2. A display stand including a pedestal; an upright carried by and projecting upwardly from the pedestal; a plurality of fingers carried at the upper portion of the upright and upon which objects to be displayed 45 may be hung; a platform carried by the upright at a lower portion thereof and having depressions therein forming seats for the objects that are to rest upon this platform, said platform having notches in its edge 50 portion that are located between adjacent seats in said platform and provided for receiving objects hung upon said fingers to position them between the objects upon said platform; an additional platform above the 55 first platform and of smaller size to clear the objects hung upon said fingers; and a positioner located above the additional platform and smaller than the first platform also to clear objects hung upon said fingers 60 and provided with openings located beside the vertical planes containing said upright and fingers whereby the objects supported upon the additional platform are clear of the objects hung upon the fingers.
- 65 3. A display stand including a pedestal;

an upright carried by and projecting upwardly from the pedestal; a plurality of fingers carried at the upper portion of the upright and upon which objects to be displayed may be hung; a platform carried by the upright at a lower portion thereof, said platform having notches in its edge portion for receiving objects hung upon said fingers to position them between the objects upon said platform, the notched portions of the platform being farther away from the upright than the object engaging portions 70 of the fingers whereby the objects hung from the fingers are inclined upwardly toward the upright; an additional platform above the first platform and of smaller size to clear the objects hung upon said fingers; and a positioner located above the additional platform and smaller than the first platform also to clear objects hung upon said fingers 75 and provided with openings overlying the additional platform and located beside the vertical planes containing said upright and fingers whereby the objects supported upon the additional platform are clear of the objects hung upon the fingers.

4. A display stand including a pedestal; an upright carried by and projecting upwardly from the pedestal; a plurality of fingers carried at the upper portion of the upright and upon which objects to be displayed may be hung; a platform carried by the upright at a lower portion thereof, said platform having notches in its edge portion for receiving objects hung upon said fingers 80 to position them between the objects upon said platform; an additional platform above the first platform and of smaller size to clear the objects hung upon said fingers; and a positioner located above the additional platform and smaller than the first platform also to clear objects hung upon said fingers 85 and provided with openings overlying the additional platform and located beside the vertical planes containing said upright and fingers whereby the objects supported upon the additional platform are clear of the objects hung upon the fingers.

5. A display stand including a pedestal; an upright carried by and projecting upwardly from the pedestal; a plurality of fingers carried at the upper portion of the upright and upon which objects to be displayed may be hung; and a platform carried by the upright at a lower portion thereof 90 and having depressions therein forming seats for the objects that are to rest upon the platform, said platform having notches in its edge portion that are located between adjacent seats in said platform and provided for receiving objects hung upon said fingers to position them between the objects upon said seats, the notched portions of the platform being farther away from the upright than the object engaging portions 95

of the fingers whereby the objects hung from the fingers are inclined upwardly toward the upright.

6. A display stand including an upright; 5 and an object supporting plate carried by the upright, said plate being bulged along lines extending across the plate to form plate strengthening ribs, the bulged portions

of the plate being integrally continued beyond the plate to form fingers upon which 10 to support objects that are to be displayed.

In witness whereof, I hereunto subscribe my name this twenty-sixth day of April, A. D. 1917.

HENRY G. SAAL.
